[57] **CLAIM**

The ornamental design for a head-mountable matrix display.

DESCRIPTION

FIG. 1 is a right rear perspective view of a head-mountable matrix display embodying our design;

FIG. 2 is a top view thereof;

FIG. 3 is a left side elevation thereof;

FIG. 4 is a rear view thereof;

FIG. 5 is a bottom view thereof;

FIG. 6 is a front view thereof; and,

FIG. 7 is a left rear perspective view thereof with arms folded.
